UNITED STATES PATENT OFFICE.

CARLETON H. BULLIS, OF CLEVELAND, OHIO.

MUSICAL INSTRUMENT.

Application filed April 27, 1922. Serial No. 556,910.

This invention relates to musical instruments.

There has been a long felt need for an instrument of convenient size, within the means of the average pipe organist, by which he may obtain pipe organ practice at home. The reed organ, in its various commercial forms, has proven unsatisfactory for this purpose. The same may be said of the piano, although many pipe organists prefer the piano to the reed organ for practice purposes, in spite of the marked differences in the touch and sound characteristics of the pipe organ and piano.

The general aim of the present invention is the provision of an instrument embodying the above requirements and well adapted for the purposes named. This is accomplished by combining in a single unitary instrument a pneumatic action of the type ordinarily employed in player pianos, together with keyboard mechanism closely approximating, both in arrangement and touch, the control mechanism commonly employed in pipe organs and to which the action is made to respond.

Other objects and advantages will hereinafter appear.

Two embodiments of this invention are diagrammatically illustrated in the accompanying drawings, in which:

Figure 1 is a diagrammatic illustration of a musical instrument constructed in accordance with the present invention.

Figure 2 is a detail of a form of electric coupler mechanism employed.

Figure 3 is a diagrammatic illustration of a musical instrument embodying certain novel features of the present invention and in which the striker pneumatics are controlled by strictly pneumatic means.

The instrument shown in Figure 1, as well as that in Figure 3, includes a case or cabinet 10 of appropriate form, enclosing the usual set of piano strings and cooperating hammers as indicated at 11 and 12, respectively.

The hammers are hingedly mounted upon a fixed rail 13 and separately actuated in a well known manner by the striker pneumatics 14. In this instance, each pneumatic 14 has a separate connection 15 with one of a series of levers 16, each of which is operatively engaged with one of a series of levers 17, which in turn are connected with their respective hammers 12, so that when any of the several striker pneumatics 14 are collapsed, the corresponding hammer is driven against its string.

The usual adjustable hammer rail 18 is preferably provided for varying the throw of the hammers. Each of the strings is also preferably normally engaged by an individual damper 19, one of which is herein shown pivotally mounted as at 20 upon the fixed rail 13, in position to be rocked away from the string by the tail 21 of the lever 17 when the corresponding hammer is actuated.

The striker pneumatics 14 are shown arranged in a triple stack, the several pneumatics of each set being separately controlled by the usual primary valves (not shown), contained within the valve-blocks 22 and in turn controlled by the usual ducts 23. The valve blocks 22 are in constant communication with an appropriate source of suction through appropriate conduits 24 and 25, the several pneumatics 14 being selectively subjected to this suction by the admission of air through their corresponding ducts 23. Since the mechanism thus far described constitutes a pneumatic action of well known construction, further description thereof is deemed unnecessary.

In carrying out the purposes of the present invention the several ducts 23, and thus the entire pneumatic action, are placed under the control of the operator by the use of mechanism closely approximating that commonly used in standard pipe organs. In each of the instruments shown, this mechanism comprises pipe organ keyboards, in the form of two manuals 26 and 26', and a pedal keyboard 27, together with appropriate operative connections between the keyboards and ducts. Thus, in the instrument illustrated in Figure 1, an electrical system is interposed between the keyboards and ducts, while in the instrument shown in Figure 3 the system of control is strictly pneumatic.

In the instrument of Figure 1, the admission of atmospheric air to each of the ducts 23 is controlled by a valve 28, carried by a lever 29, pivotally mounted, as at 30, upon a fixed rail 31. Each lever 29 carries an armature 32 cooperating with and actuated by an electro-magnet 33. One side of each electro-magnet is connected through a lead 34 to one side of a battery 35 or other convenient electrical source, while the other side is connected to an electric coupler mechanism of well known form. It will suffice here to say that this coupler mechanism includes a switch board or panel provided upon one face thereof with a series of horizontally spaced, ver-

tically extending metal strips 36 constituting electric contact plates. The number of contact plates corresponds to the number of piano hammers and consequently to the number of electromagnets employed. Each electromagnet is electrically connected with one of the contact plates through a lead 37. A plurality of transversely extending switch bars 38, 39, 40, 41, 42, 43, 44 and 45 are arranged at one side of the switch board adjacent the contact plates. Each bar is pivotally mounted for rocking movement about a horizontal axis 46 and is controlled by a pneumatic 47 connected thereto by a link 48.

15 Each bar is provided with a set of contact fingers 49 arranged to simultaneously engage certain of the contact plates 36 when the bar is rocked to the position shown in Figure 2.

The several switch bars normally assume 20 positions in which the fingers 49 are out of contact with the contact plates 36. In this position, the pneumatics 47 are expanded. To rock any of the bars to the position of Figure 2 its corresponding pneumatic 47 is collapsed. 25 The several pneumatics 47 are associated with a valve block 50 similar to those employed in connection with the striker pneumatics 14, so that the collapse of any selected pneumatic 47 is effected by the admission of atmospheric air through the duct 51 associated therewith.

The several ducts 51 are controlled by separate stops 52. In this instance, each stop is pivotally supported, as at 53, and is provided 30 at one end with a valve 54 for cooperation with a duct 51 and at its other end with a finger piece 55 projecting outwardly from the cabinet within convenient reach of the operator. The normal position of these stops 40 is such that the end of the ducts 51 are closed by the valves 54. By depressing the finger piece of any of the stops, the valve 54 is lifted to open position, air is admitted to the corresponding duct 51, and the selected pneumatic 45 47 is collapsed to rock the corresponding switch bar to the position of Figure 2.

In the instrument shown in Figure 1, each switch bar carries the usual bundle 56 of insulated wires having individual electrical 50 connections 57 with the several contact fingers 49 carried by the bar. Bars 38, 39 and 40 are associated with the upper manual 26, the number of fingers 49 of each corresponding 55 to the number of keys in the upper manual, each wire of the bundle 56 having an electrical connection 58 with a contact point 59 beneath one of the keys. Similarly, the number of fingers 49 carried by each bar 41, 42 and 43, corresponds to the number of keys in 60 the lower manual 26', the wires of each bundle 56 thereof having separate connections 58 with contact points 59 beneath the respective keys of that manual. There is also a contact 65 point 59 beneath each key of the pedal board 27 corresponding to a finger 49 on each of the

bars 44 and 45, separate electrical connections 58 being established between these contact points and the respective wires of the bundles 56. Each key is pivotally mounted, as at 60, upon a fixed rail 61 and is yieldably supported by a spring 62. Each key carries a contact finger 63 electrically connected, as indicated at 64, with the other side of the battery 35, and arranged to engage the contact points 59 therebeneath when the key is depressed. 75

Let it be assumed, for purposes of explanation, that the instrument has a compass of eighty five notes. The same number of hammers 12, striker pneumatics 14, ducts 23, electro-magnets 33 and contact plates 36 are, of course, provided. Each manual contains a smaller number of keys, say sixty one, and the pedal board only thirty two. Each of the switch bars 38, 39, 40, 41, 42 and 43, then carries sixty one contact fingers 49, while each of the bars 44 and 45 is provided with thirty two. The contact fingers of each of the bars 38 and 41 are arranged to make and break contact with those plates 36 corresponding to the sixty one notes at the upper end of the compass; the contact fingers of each of the bars 40 and 43 are arranged to make and break contact with those plates 36 corresponding to the sixty one notes at the lower end of the compass; and the contact fingers of each of the bars 39 and 42 are disposed to make and break contact with an intermediate range of sixty one plates, for instance, twelve notes below the first mentioned range and twelve notes above the other. The contact fingers of bar 44 are disposed to cooperate with those plates corresponding to the lowermost thirty two notes of the compass and contact fingers of bar 45 are disposed to cooperate with thirty two plates corresponding to a range 105 twelve notes higher.

Any one or more of the switch bars may be rocked to switch closing position by a selective manipulation of the stops 52, as above pointed out. When, for instance, one of the stops is manipulated to effect rocking of the bar 38 to the position of Figure 2, the contact points 59 of the upper manual are electrically connected with the sixty one plates 36 corresponding to upper sixty one notes 115 of the scale. A depression of any key of this manual then closes the circuit from the battery 35, through lead 64, contact finger 63 of the selected key, contact point 59, contact finger 49 of the switch bar, contact plate 36, electromagnet 33 and back to the battery. The electromagnet is thus excited to lift the armature 32 and valve 28, air is admitted through the duct 23, and the corresponding pneumatic 14 is actuated to drive its hammer against the string. The various notes of this particular range are thus made to respond to the keys of the upper manual. By operation of the bars 39 and 40 in a similar manner, other ranges of notes may be made 125 130

to respond to the upper manual. In this way, one or more notes may be made to simultaneously respond to the depression of a single key of the upper manual dependent upon the setting of the stops. Similarly, various ranges of notes may be made to respond to the lower manual or to the pedal keyboard.

In order to obtain a swell effect, mechanism controlled by a swell pedal 65 is preferably provided. In this instance, this mechanism includes mechanical connections, by which the throw of the hammers is varied, and additional means for varying the intensity of the air tension within the pneumatic action. To vary the throw of the hammers, the hammer rail 18 is pivotally mounted, as at 66, in a well known manner, and is provided with a lever arm 67, connected through a link 68 with a lever 69, pivotally mounted in the bottom of the cabinet. This lever is actuated and controlled by the swell pedal 65 through a link 70 connected with an arm 71 secured to the pedal. A friction clamp 72 is preferably employed to yieldably retain the lever 69 and swell pedal in any position in which they may be set.

An expression pneumatic 73, such, for instance, as that described in the patent to Frank J. Clark, No. 1,384,010, is preferably employed for modifying the air tension in the pneumatic action. This pneumatic 73 tends to collapse under the influence of the air tension in the conduit 24 to move the valve 74 thereof toward open position and thus permit air to bleed into the conduit to maintain a definite air tension therein. The collapse of pneumatic 73 is resisted by a spring 76, whose tension thus determines the degree of vacuum in the conduit 24 and the player action. This spring is connected to one end of a lever 77, rockably mounted upon a fixed pivot 78, and connected at its other end to the swell pedal 65 through a link 79 and lever 80. Thus it will be seen that when the swell pedal 65 is rocked in a clockwise direction (Fig. 1), the hammer rail 18 is shifted to increase the stroke of the hammers and the tension in spring 76 is simultaneously increased to increase the air tension in the pneumatic action. The tone volume is thus materially increased. To decrease the tone volume the pedal 65 is rocked in the other direction.

The instrument shown is also equipped with a sustaining pedal 81. This pedal carries a valve 82 which normally prevents the admission of air to a duct 83. Duct 83 leads to a valve block 84 controlling a pneumatic 85 in a manner similar to that described in connection with the striker pneumatics 14. Pneumatic 85 is operatively connected through a link 86 with a rail 87 pivotally mounted adjacent the lower ends of the damper levers 88. The arrangement is such that when the pedal 81 is in valve closing

position, the pneumatic 85 is expanded and the rail 87 is out of engagement with the damper levers. When the pedal is rocked in a counter clockwise direction, however, valve 82 is lifted to open position, air is admitted through duct 83 and the pneumatic 85 is collapsed. This causes the rail 87 to be rocked against the lower ends of the damper levers to thus withdraw the dampers 19 into inactive position out of engagement with the strings.

In the instrument illustrated in Figure 3, the ducts 23 corresponding to the several striker pneumatics 14 are controlled by strictly pneumatic means. They are all shown connected with a bleed box 89 of standard type, which may or may not be employed in the instrument first described. Each duct 23 is connected to two ducts 90 leading to separate fixed rails 91 associated with the two manuals 26 and 26', while some of the ducts 23, preferably those associated with the group of striker pneumatics corresponding to the lower notes of the scale, are connected with ducts 92 leading to a fixed rail 93 associated with the pedal board. Each of the manual keys is rockably mounted upon a fixed rail 94, and is provided with a valve 95 cooperating with the end of a duct 90. A spring 96 yieldably retains each valve 95 in closed position. Similarly, each pedal key is provided with a valve 97, cooperating with a duct 92, and with a spring 98 which yieldably retains the valve in closed position. When any of the keys of either manual or of the pedal board is depressed, valve 95 or 97 is lifted to open the corresponding duct 90 or 92, and the corresponding striker pneumatic 14 is collapsed to drive the corresponding hammer against a string.

It is obvious that, if desired, this instrument may be provided with expression and sustaining mechanisms, such, for instance, as those hereinabove described.

Various changes may be made in either embodiment of the invention hereinabove described, without departing from or sacrificing any of the advantages of the invention as defined in the appended claims.

I claim:

1. A self contained musical instrument comprising a cabinet, a manual keyboard attached thereto, a pedal keyboard attached thereto, a pneumatic action including a plurality of striker pneumatics contained in said cabinet, means under the control of said manual keyboard for controlling the operation of a series of said pneumatics, and means under the control of said pedal keyboard for controlling the operation of another series of said pneumatics.

2. A self contained musical instrument comprising a cabinet, a manual keyboard attached thereto, a pedal keyboard attached thereto, a pneumatic action including a plu-

rality of striker pneumatics contained in said cabinet, a series of valves for controlling the operation of said pneumatics, and means under the control of the operator for placing certain of said valves under the control of the manual keyboard or under the control of said pedal keyboard.

3. A self contained musical instrument comprising a cabinet, a plurality of keyboards attached thereto, a pneumatic action including a plurality of striker pneumatics contained in said cabinet, a series of valves for controlling the operation of said pneumatics, and means under the control of the operator for placing said valves under the control of one or another of said keyboards.

4. A self contained musical instrument for the purposes named, comprising a cabinet, a pneumatic action including a plurality of striker pneumatics within said cabinet, means including a manual and pedal keyboard attached to said cabinet and means interposed between said keyboard and said pneumatics for selectively placing said pneumatics in one or more groups under the control of said keyboard.

5. A self contained musical instrument for the purposes named, comprising a cabinet, a pneumatic action including a plurality of striker pneumatics within said cabinet, a manual and pedal keyboard attached to said cabinet, coupled mechanism for selectively placing said pneumatics in one or more groups under the control of said keyboard, and stops for controlling the operation of said coupler mechanism.

6. A self contained musical instrument for the purposes named, comprising a cabinet, a pneumatic action including a plurality of striker pneumatics within said cabinet, manual and pedal keyboards attached to said cabinet, and manually controlled means for selectively placing one or more groups of said pneumatics under the control of either of said keyboards.

7. In a musical instrument the combination of a pneumatic action including a set of striker pneumatics, means including a manual and pedal keyboard for controlling the operation of said pneumatics, and means under the control of the operator for varying the air pressure in said action to vary tone intensity.

8. A self contained musical instrument comprising a keyboard, a pneumatic action including a plurality of striker pneumatics, valves for controlling the action of said pneumatics, electrically operated means for effecting the actuation of said valves, and manually controlled electric coupler mechanism associated with said means and said keyboard for rendering certain of said valves responsive to said keyboard.

9. A self-contained musical instrument for the purpose named comprising a cabinet, a series of strings and cooperating hammers therein, power operated means for operating said hammers, a pedal keyboard attached to said cabinet, a manual keyboard attached to said cabinet, individual controls for said hammers, and means under the control of the operator for placing certain of said controls under the control of said manual or pedal keyboards selectively.

10. A self-contained musical instrument for the purpose named comprising a cabinet, a series of strings and cooperating hammers therein, power operated means for operating said hammers, a pedal keyboard attached to said cabinet, a manual keyboard attached to said cabinet, individual controls for said hammers, means under the control of the operator for placing certain of said controls under the control of said manual or pedal keyboards selectively, and means under control of the operator for varying the intensity of action of the hammers against the strings.

In witness whereof, I hereunto subscribe my name this 24th day of April, 1922.

CARLETON H. BULLIS.
